FIG. 1 is a perspective view of a container for a ladder of my design;

FIG. 2 is a front elevational view thereof;

FIG. 3 is a rear elevational view thereof;

FIG. 4 is an end elevational view of the left end thereof;

FIG. 5 is an end elevational view of the right end thereof;

FIG. 6 is a top plan view thereof; and,

FIG. 7 is a bottom plan view thereof.

The broken lines of a step ladder in FIG. 1 are not part of the design of the container for a ladder.
